UNITED STATES PATENT OFFICE.

CHRISTOPHER J. ARCHIBALD, OF NEW YORK, N. Y.

CLOTHES-LINE HOLDER.

SPECIFICATION forming part of Letters Patent No. 738,873, dated September 15, 1903.

Application filed April 27, 1903. Serial No. 154,388. (No model.)

To all whom it may concern:

Be it known that I, CHRISTOPHER J. ARCHIBALD, a citizen of the United States, residing at New York, in the county of New York and 5 State of New York, have invented certain new and useful Improvements in Clothes-Line Holders, of which the following is a specification, such as will enable those skilled in the art to which it appertains to make and use 10 the same.

The object of this invention is to provide improved means for supporting clothes-lines adapted to be connected with the window-frame or other structure and with a suitable 15 support at a distance therefrom; and with this and other objects in view the invention consists in a device of the class specified constructed as hereinafter described and claimed.

The invention is fully disclosed in the following specification, of which the accompanying drawings form a part, in which the separate parts of my improvement are designated by suitable reference characters in each of the views, and in which—

25 Figure 1 is a side elevation showing my improved support for clothes-lines and the method of using the same; Fig. 2, a plan view thereof, and Fig. 3 a front view of one of the bow-shaped pieces forming part of my improved support for clothes-lines.

30 In the drawings forming part of this specification I have shown at *a* a support, which may consist of an ordinary post or pole and which is provided with a hook *a*², and I have 35 also shown at *b* a part of the window-frame, which is provided with a hook *b*², and in the practice of my invention I provide two similar curved or bow-shaped pieces *c*, each of which is provided with an eye or similar device *c*², which in practice are connected with the hooks *a*² and *b*², as shown. Each of the

parts *c* is forked at the lower end, as shown at *c*³, and provided with a double fork *c*⁴ at the upper end, in which are mounted two rollers *c*⁵, and the lower end is also provided with a roller *c*⁶. Mounted on one set of the rollers *c*⁵ is a cord or rope *d*, the ends of which are connected at *d*² in any desired manner, and mounted on the other set of the rollers *c*⁵ and passing around the rollers *c*⁶ is another 45 cord *e*, the ends of which are connected at *e*² in any desired manner. As thus constructed it will be seen that clothes or other articles may be hung on the bottom reaches of both of the cords *d* and *e* and both of said cords 50 may be pulled around the rollers on which they are placed in the usual manner.

My invention is not limited to the exact details of the construction herein shown and described, and many changes therein and modifications thereof may be made without departing from the spirit of my invention or sacrificing its advantages.

Having fully described my invention, what I claim as new, and desire to secure by Letters 65 Patent, is—

A clothes-line support comprising two separate bars or members provided centrally with attaching devices and adapted to be supported in a vertical position and provided at their 70 upper ends with two rollers and at their lower ends with single rollers, substantially as shown and described.

In testimony that I claim the foregoing as my invention I have signed my name, in presence of the subscribing witnesses, this 25th day of April, 1903.

CHRISTOPHER J. ARCHIBALD.
